Patented Apr. 13, 1926.

UNITED STATES PATENT OFFICE.

EPHRAIM S. RICHARDS, OF LAKE PROVIDENCE, LOUISIANA.

INSURANCE-VENDING MACHINE.

Application filed May 5, 1923. Serial No. 636,906.

To all whom it may concern:

Be it known that I, EPHRAIM S. RICHARDS, a citizen of the United States, residing at Lake Providence, in the parish of East Carroll and State of Louisiana, have invented a new and useful Insurance-Vending Machine, of which the following is a specification.

This invention aims to provide novel means whereby strips of paper may be dispensed, subject to a coin-control, the device being of peculiar utility in connection with the vending of insurance policies, a carbon copy of the policy being retained, and novel means being supplied for operating and controlling the various movable parts of the structure.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in top plan, a device constructed in accordance with the invention; Figure 2 is a section on the line 2—2 of Figure 1; Figure 3 is a top plan, parts being removed in order that the machinery within the cabinet may be seen; Figure 4 is a section taken approximately on the line 4—4 of Figure 3; Figure 5 is a section taken approximately on the line 5—5 of Figure 2.

In carrying out the invention, there is provided a support or cabinet, which is denoted by the numeral 1. The top of the cabinet is made up of oppositely slanting portions 2 and 3 connected by a raised rib 4. The portion 2 of the top of the cabinet has an opening 5 through which the writing is done, during the filling out of the policy. Any suitable means (not shown) may be supplied for covering the opening 5 when the machine is not in use, but since the operation of a coin-controlled mechanism is not affected by a closure of any kind, no

closure has been delineated, that detail being 55 left to the taste of the manufacturer or user. The cabinet 1 carries a table 6 located near the opening 5. This table supports the policy whilst the same is being filled out. Separators 7 are carried by the top of the 60 cabinet and are located along opposite edges of the opening. The utility of the separators 7 will be made manifest hereinafter.

A frame 8 is supported within the cabinet 1, the frame being U-shaped in cross section, 65 if desired, as shown in Figure 5. Shafts 9, 10, 11, 12 and 14 are disposed horizontally in the cabinet 1 and are journaled in the side portions of the frame 8. The shafts 10, 11 and 12 are disposed in horizontal alignment near the bottom of the cabinet. The shafts 9 and 14 are located in about the same horizontal plane and are disposed respectively, above the shafts 10 and 12. The shaft 11 is located between the shaft 10 and 12. A supply reel 15 is mounted on the shaft 9. A take-up reel 16 is mounted on the shaft 14. The strip 17 of paper on which the duplicate policy is printed is wound on the reel 15 and is adapted to be 80 taken up by the reel 16. The shaft 10 carries a supply reel 18. There is a take-up reel 19 on the shaft 12. A strip 20 of carbon paper is wound on the reel 18 and is adapted to be taken up by the reel 19. 85 There is a reel 21 on the shaft 11. This reel carries the strip 22 of paper on which the original policy is printed. The strips 17, 20 and 22, superposed in the order named, pass over idle rollers 23 journaled in the upper 90 portions of the frame 8. They pass, also across the table 6, beneath the opening 5. As shown in Figure 5, the separators 7 are interposed between the strip 22 which carries the original policy, and the strip 20 of carbon paper, whilst the various strips 17, 20 and 22 are passing across the opening 5 in the top of the cabinet. Vertically aligned guide rollers 24 and 25 are journaled on the frame 8 and are located slightly in advance of the opening 5, the strips 17, 20 and 22 95 impinging between the rollers 24 and 25, immediately before they arrive at the opening 5. The roll 24 is accommodated in the rib 4 that is fashioned in the top of the cabinet 1. Sprocket wheels 75 are mounted to rotate on the shafts 9, 10, 11, 12 and 14. A sprocket chain 26 is engaged about the 100 105

sprocket wheels 75. Compression springs 27 surround the shafts and abut against the sprocket wheels 75 and against the frame 8. The sprocket wheels 75, thus are held 5 frictionally against the various rollers, for instance, the rollers 16 and 19 of Figure 5, so that the sprocket chain 26 is actuated, the rollers will be rotated, the sprocket wheels being connected to the rollers and to 10 the shafts by what amounts to a friction clutch. Nuts 28 are threaded on the outer ends of shafts 9, 10, 11, 12 and 14 and by turning these nuts, the shafts may be given a slight endwise movement, thereby to adjust 15 just the compressive effect of the springs 27.

A lever 29 is supported for vertical swinging movement in the cabinet 1, as shown at 20, that is, for swinging movement in a vertical plane. The lever 29 operates in a slot 21 in the top of the cabinet 1. Pivot elements 32 are carried by the lever 29 and operate in elongated slots 33 which are fashioned in converging levers 34 having cooperating jaws 35 (Figure 4) at one end. At 25 their opposite ends the levers 34 are pivoted to links 36, the inner ends of the links being pivotally united. When the lever 29 swings in the direction of the arrow A in Figure 2, the jaws 35 will be caused to grip and 30 advance the strips 22, 20 and 17, because the pivotally connected inner ends of the links 36 are united by a connection 37 with the lever 29, the connection 37 being pivoted at 38 to the lever 29, and a toggle thus being 35 afforded whereby the jaws 35 will be caused to grip the strips as aforesaid. Amplifying the foregoing, it may be stated that, although the jaws 35 appear spaced a trifle from the strips in Figure 2, this showing 40 was made to avoid a confusion of lines, and to the end that the inner extremities of the jaws might be clearly seen. As a matter of fact, the jaws 35 drag with a frictional hold upon the strips, and, when the lever 29 is 45 swung in the direction of the arrow A in Figure 2, the lever 29 first moves independently of the levers 34, because the pivot elements 32 are received in the slots 33. This independent movement of the lever 29 is 50 small, and perhaps inappreciable, but it is sufficient to permit the lever 29 to exert a pull on the connection 37, thereby tilting the levers 34 by way of the links 36, and causing the jaws 35 to grip the strips. 55 When the lever 29 swings in a direction opposite to that indicated by the letter A in Figure 2, the hold of the jaws 35 on the strips 17, 20 and 22 will be released. In view of the construction last above described, a means for feeding the strips is 60 provided, which means is independent of the rollers 16 and 19, and the strips are not fed by tension alone. Further, since the strip 22 has a free end, and is not operated by a take-up roll, the jaws 35 and parts associated 65

therewith have a peculiarly useful function. The edge of the top of the cabinet which is marked by the numeral 39 affords a means whereby the purchaser may tear off his policy from the strip 22, the carbon paper 70 passing on to the take-up reel 19, and the duplicate policy passing to the take-up reel 16. A chain tightener 40 of any desired sort may be used for taking the slack out of the driving chain 26. 75

A coin chute 41 is mounted for longitudinal reciprocation and for tilting movement, in the part 2 of the top of the cabinet 1. The lower end of the coin chute 41 is pivoted at 42 to the lever 29. The coin chute 80 41 is supplied at its lower end with oppositely disposed openings 43 and 44 and has a concaved seat 41^a at its lower end.

An arm 45 is pivoted at 46 to the lever 29 and is adapted to operate in the opening 43 85 of the coin chute 41. A link 47 is pivoted to the arm 45 and is pivoted to an arm 48 on a shaft 49 mounted to rock in the lever 29, the shaft having a dog 50 adapted to cooperate with the upper run of the sprocket 90 chain 26. A very light spring 51 is connected to the lever 29 and bears on the arm 48. An ejector 52 is supported in the cabinet 1 and is adapted to enter the opening 43 in the coin chute 41. 95

When a coin C is deposited in the coin chute 41, the coin rolls downwardly, tilting the arm 45, the link 47 rocking the shaft 49 through the instrumentality of the arm 48 and causing the dog 50 to engage the upper run of the sprocket chain 26, the coin being held on the seat 41^a by the arm 45, as shown 100 in Figure 4. Then, when the lever 29 is swung in the direction of the arrow A in Figure 1, the jaws 35 together with the reels 16 and 19, advance the strips 17, 20 and 22 with respect to the opening 5 in the top of the cabinet. The jaws 35 and the lever 29 may pull the strips ahead faster than the strips are fed off the rollers when the rollers are power-operated through the instrumentality of the chain 26 and the dog 50; and it is in order to prevent the strips from being torn apart, that the friction clutch afforded by the springs 27, is provided. The purchaser fills out his policy, writing through the opening 5, and tears off his original policy across the edge 39 of Figure 1. When the lever 29 has been swung far enough in the direction of the arrow A in Figure 2, the ejector 52 enters the opening 43 in the coin chute 41 and knocks the coin out of the coin chute, through the lower end of the opening 43, whereupon the dog 50 is disengaged from the chain 26 by the action 110 of the spring 51 and it will be impossible for a person to operate the machine, and secure another policy, until a coin is deposited in the chute 41. During the dislodging of the coin C, the dog 50 simply enters a little 115 120 125 130

further into the chain 26 but does not bind on the chain and prevent the dislodging of the coin.

What is claimed is:—

- 5 1. In a device of the class described, a support, feed and take-up reels journaled in the support, a flexible element connecting the reels, a lever fulcrumed on the support, a dog carried by the lever and normally disengaged from the flexible element, means for operating the dog, a chute so located as to direct a coin against said means and retain the coin, thereby to engage the dog with the flexible element, and means for displacing the coin from the chute after the lever has been swung through a predetermined arc.

2. In a device of the class described a support, feed and take-up reels journaled in the support, a flexible element 20 connecting the reels, a lever fulcrumed on the support, a dog carried by the lever and normally disengaged from the flexible element, a chute pivoted to the lever and adapted so to dispose a coin that the coin 25 will engage the dog with the flexible element, and an ejector located in the path of the chute and constituting means for displacing a coin from the chute after the lever has swung through a predetermined arc. 30

In testimony that I claim the foregoing as my own, I have hereto affixed my signature.

EPHRAIM S. RICHARDS.
